UNITED STATES PATENT OFFICE.

CHARLES H. WOODWARD, OF OCEAN SPRINGS, MISSISSIPPI, ASSIGNOR TO REFRIGERATOR CAR EQUIPMENT CO., OF CHICAGO, ILLINOIS, A CORPORATION OF WASHINGTON.

DEVICE FOR REGULATING THE TEMPERATURE IN CLOSED VEHICLES.

1,355,205.

Specification of Letters Patent. Patented Oct. 12, 1920.

Application filed June 18, 1917. Serial No. 175,535.

To all whom it may concern:

Be it known that I, CHARLES H. WOODWARD, a citizen of the United States, residing at Ocean Springs, in the county of

5 Jackson and State of Mississippi, have invented a certain new and useful Improvement in Devices for Regulating the Temperature in Closed Vehicles, of which the following is a specification.

10 This invention relates to devices for regulating the temperature in closed vehicles, and has for its object to provide a means for easily and quickly draining said refrigerating apparatus. The invention is illustrated 15 in the accompanying drawings, wherein—

Figure 1 is a view showing the apparatus applied to a car.

Fig. 2 is a sectional view taken on line 2—2 of Fig. 1.

20 Fig. 3 is a plan view of one of the openings in the roof of the car and the parts associated therewith.

Like numerals refer to like parts throughout the several figures.

25 In carrying out my invention I provide at each end of the car one or more tanks 1 and 2. These tanks are connected by pipes 3 and 4, and a temperature varying liquid is circulated through the tanks and pipes.

30 In the construction shown, a portion of the tank projects upwardly through the roof of the car, each tank being provided with an opening through which liquid is inserted, the opening being normally closed 35 by closing devices 5 which may be plugs or of any other form. The liquid may be drawn out of the apparatus when it is desired to recharge the apparatus.

In the construction shown, there is a discharge pipe 6 which connects with some 40 part of the apparatus, such for example, as the pipe 4, said discharge pipe being arranged so that the liquid can be discharged at any point desired. As herein shown, the 45 end 7 of the discharge pipe empties into a waste pipe 8 which is used to conduct away the moisture which settles on the pipes 3 and 4. These pipes 3 and 4 are provided with troughs 9 to collect this moisture, the 50 moisture passing into the trough 10 and then into the waste pipe 8. The discharge pipe 6 is provided with a valve 11. This valve has a controlling device consisting of a rod 12 which projects up through the

top of the car. By rotating this rod 12, 55 the valve may be opened or closed. The rod is preferably provided with the handle 13 by means of which it is controlled.

It will be seen, for example, if the valve 11 should be left open, or partially open, 60 and the vehicle started on its journey, the liquid would escape and the cargo in the car would become ruined. I provide some means for absolutely insuring against this condition. In the construction shown, an 65 obstructing part 14 is connected with the rod 12 and is arranged so that when the valve is open, or partially open, this obstructing part projects into the opening 15 into which the closing device 5 fits. It will 70 thus be seen that whenever the rod 12 is moved to open the valve 11 to drain the car, this obstructing device is automatically moved into a position where it projects into the opening 15. If, for example, it is attempted to close this opening before the valve is completely closed, the closing device 75 engages the obstructing device, and hence the receptacle cannot be closed. This attracts the attention of the operator and 80 compels him to close the valve before he can put the closing device in position. When he moves the rod 12 so that the valve 11 is closed, the obstructing device 14 passes out of the way of the closing device 5. It will 85 thus be seen that by means of this device, the drainage system cannot be left open so that the liquid will drain out of the apparatus after the car is loaded.

I claim:

1. A device for regulating the temperature in closed vehicles comprising separated tanks connected with the vehicle, pipes connecting said tanks, a charging opening for each tank, closing devices for said charging 95 openings, a discharge pipe connected with said system, a valve controlling said discharge pipe, an actuating device for said valve, said actuating device located at one side of the charging opening and the closing device therefor when the closing device is in its closed position, a laterally extending obstructing device connected with the said actuating device and normally entirely outside of the boundaries of said 100 charging opening when said valve is closed, one end thereof arranged to project into one of said charging openings when the valve is 105

- open so as to prevent the closing device from being moved to its closing position and a handle for controlling the actuating device for the valve and said obstructing device.
2. A device for regulating the temperature in closed vehicles comprising a plurality of separated tanks connected with said vehicles and located at opposite ends thereof, pipes connecting said tanks, said tanks provided with charging openings, a single discharge pipe for discharging the material from all of said tanks and pipes, a valve controlling said discharge pipe, a rod connected with said valve and projecting through the top of the vehicle at one side of one of said charging openings, said rod adapted when moved to open and close said valve, an obstructing device connected with said rod and projecting into the charging opening of one of said tanks when the valve is open, so as to prevent the closing device from being moved to its closed position, said obstructing device being moved out of the way of the closing device so as to be entirely at one side of the said closing device when the closing device is in its closed position, and a handle always out of the

way of the closing device and connected with said rod for simultaneously moving 30 the valve and the obstructing device.

3. A device for regulating the temperature in closed vehicles comprising a tank containing temperature varying material said tank having an opening at the top, a 35 cover for said opening, a discharge device connected with the tank, a valve for controlling said discharge device, a rod connected with said valve for moving it, a handle connected with said rod, a projecting 40 arm connected with said rod, a reciprocating obstructing part connected with said arm, the end thereof adapted to project beneath said cover when the valve is open and to be withdrawn from beneath said cover 45 when the valve is closed, whereby the cover can only be placed in position when the valve is closed.

In testimony whereof I affix my signature in the presence of two witnesses this 29th 50 day of May, 1917.

CHARLES H. WOODWARD.
